UNITED STATES PATENT OFFICE

HENRY L. PITMAN, OF WESTFIELD, NEW JERSEY, ASSIGNOR, BY MESNE ASSIGNMENTS,
TO ELLIOTT-FISHER COMPANY, OF NEW YORK, N. Y., A CORPORATION OF DELAWARE

COMBINED TYPEWRITING AND COMPUTING MACHINE

Application filed June 2, 1926. Serial No. 113,133.

This invention relates to combined typewriting and computing machines of the Underwood-Hanson type, and particularly to improvements therein whereby the usual functions of the machine are facilitated and accomplished with greater convenience to the operator, and whereby the costs of manufacturing and maintaining said machines are substantially reduced.

In said type of machines the numeral-keys of the typewriter, when operated while the carriage is in a computing zone, set corresponding index-pins in rack-bars of a computing mechanism that is below the typewriter. These rack-bars subsequently run the digits indexed therein into computing wheels. To enable any numeral-key to set an index-pin in any rack-bar, a so-called pin-setting frame is interposed between members depending from the numeral-key-levers and the index-pins on the rack-bars. The pin-setting frame includes pin-setting bars, one for each numeral-key, arranged transversely of the rack-bars and over the index-pins therein. Each pin-setting bar is depressible by an operation of a corresponding numeral-key, and, when projected, is normally in advance of the corresponding transverse row of index-pins. To enable the pin-setting bar to set an index-pin, the rack-bar in which the pin is to be set must be slightly advanced, so that the index-pins therein are directly under the pin-setting bars. There is usually a plurality of said rack-bars, and they are advanced one after the other in denominational order as the typewriter-carriage passes in letter-feeding steps through a computing zone.

One object of the present invention is to provide improved and simplified means whereby the pin-bars are thus advanced seriatim. Means heretofore provided include a settable one-way acting tappet on the typewriter-carriage, which actuates jacks interposed between said tappet and thrust-rods extending downwardly toward a mechanism whereby the thrust imparted to an actuated thrust-bar is translated into the slight advance movement of the corresponding rack-bar necessary to bring the index-pins in said bar under the pin-setting bars. A denomina-

tional tabulating mechanism is usually employed, and said tappet is usually set in a certain relation to the usual tabulating counter-stop.

According to the present invention, the tappet is combined with and forms an integral part of a tabulating counter-stop, so that when a counter-stop is set, a tappet is set at the same time, said tappet also directly engaging the ends of the thrust-rods, as the carriage moves through a computing zone.

An important feature of the invention is that, where several registers are employed and spaced apart in the direction of carriage-travel, the several corresponding sets of ends of the thrust rods or jacks engaged by the tappets are grouped together in one zone contiguous to the place from which the denominational tabulating stops are projected into the path of a counter-stop on the carriage. The different sets of jacks are arranged in said zone in set-defining rows, one row being forward of the other. The several sets of jacks reach from said one zone toward spaced sets of members of the corresponding registers, whereby the rack-bars are advanced seriatim in inverse order to the seriatim operation of the set of thrust rods or jacks.

One advantage of having the tappet-engaged ends of all the thrust-rods brought to one zone is that it facilitates the setting of the tabulating stops and jack-engaging tappets thereon, it being readily understood that it is much easier to set all the stops with reference to only one zone than it would be to set them with reference to several zones, as was necessary heretofore when the tappet-actuating ends of the several sets of thrust rods or jacks were in different zones due to being carried straight up from the spaced-apart sets of computing members to which they are connected.

Another advantage resulting from the tappet-engaged ends of the different sets of jacks being all in one zone is that the bar on which the tappet is settable may be materially shortened, and that the over-all width of the typing carriage on which said bar is mounted may therefore be correspondingly reduced.

where the length of said bar determines said over-all width.

Still another advantage resulting from bringing the aforesaid jacks all to said one zone is that only one tappet need be employed when it is desired to compute in several registers simultaneously, it being readily understood that by reason of the different rows of jacks being brought together and the rows placed one ahead of the other in one zone, the tappet may be so constructed as to simultaneously engage and actuate more than one row of jacks. Heretofore when the tappet-engaged jack-ends of the several sets of jacks were grouped in different zones, it was necessary to set a tappet for each of the several registers in which it was desired to compute simultaneously.

The patent to O. W. Olmsted, No. 1,224,314, dated May 1, 1917, discloses a tappet combined with a tabulating counter-stop to directly engage a thrust-rod. The present invention as related to this feature is an improvement over the invention in said patent, in that the tappet has been devised to engage and actuate the thrust-rod in either direction of the carriage movement. In said patent the tappet is spring-pressed and pivoted on the counter-stop in such a way that it acts as a one-way pawl, and is consequently caused to be diverted by a backward movement of the carriage through a computing zone. In said patent means whereby the ends of the thrust-rod are caused to be withdrawn from the path of the tappet are actuated by operation of the back-space key. In the present invention such withdrawal of the thrust-rod upon operation of the back-space key is unnecessary, because the tappet is not diverted by the ends of said thrust-rod in a backward movement of the carriage. Another advantage gained by the use of a tappet integral with the tabulating counter-stop is that such a tappet may be made more rugged and at less cost than a spring-pressed pivoted pawl tappet. The actuating surface of the tappet is V-shaped and the apex of the V slightly rounded, and said surface is hardened and highly polished. The ends of the thrust-rod are substantially semi-spherical in shape and are also hardened and highly polished. By means of these hardened and highly polished surfaces the friction between said ends and the tappet is reduced to a minimum.

The ends of the thrust-rod are necessarily arranged at or near the place from which the denominational stops are projected into the path of a tabulating counter-stop. From said place the thrust-rod are directed downwardly toward a mechanism whereby the rack-bars are not only advanced seriatim, but in inverse order to the seriatim operation of the thrust-rod. Another object of the present invention is to accomplish this inversion of the order of operation by improved means which

may be applied to machines having more than one set of rack-bars for operating more than one set of computing wheels. In the aforesaid patent to Olmsted, said inversion was accomplished by offsetting one end of each thrust-rod from the other end. The arrangement of a full complement of such rods requires a sort of interweaving of said rods, as shown in said patent, which is not adaptable to machines having more than one set of rack-bars.

To accomplish said inversion in the present invention there is provided for each rack-bar a bell-crank lever with one arm adjacent to the rack-bar and another arm in the plane toward which the corresponding thrust-rod is normally directed. The two arms of each bell-crank lever are connected by a U-shaped yoke, and the yokes of the different levers are of varying depths, so that when a full complement of bell-crank levers is mounted on a common fulcrum shaft a nested arrangement of said yokes may be effected. Said yokes are disposed in two groups, each group spaced about 90 degrees from the other in order to avoid undue depth of the outer yokes. It will be understood that the number of groups in which said yokes are disposed depends on the number of bell-cranks mounted on the common fulcrum shaft. It will also be understood that the reason for the aforesaid inversion of the order of operation is that in writing a row of digits, the carriage moves in letter-feeding steps from right to left, and consequently actuates the thrust-rod from right to left, and that said digits must be indexed in the rack bars from left to right. A plurality of simple levers, one for each bell-crank, is interposed between the lower ends of the thrust-rod and corresponding bell-crank arms. Said levers mounted on a common fulcrum shaft give the bell-cranks their proper direction of rotation. One advantage gained by the use of said bell-cranks, each made of one piece, is that there is required a number of parts substantially less than in the mechanism heretofore used for effecting the same purpose.

Another object of the present invention is the provision of improved and simplified means for silencing the computing mechanism. Such silencing is preferably accomplished by making the means whereby the rack-bars are advanced seriatim ineffective as heretofore, but by simplified means. To this end connections between the aforesaid bell-cranks and the rack-bars are made by means of members interposed between the rack-bars and the bell-crank arms adjacent to said rack-bars, said members being shiftable into and out of effective position. Suitable means are provided to shift all of said members into ineffective position simultaneously. In the preferred form of the invention said members are thrust-bars, each hav-

ing one end pivoted to a corresponding arm of the bell-crank and the other end normally engaging a projection from the adjacent rack-bar. A common bail embraced by a suitable slot in said other end is effective to shift all of said members from their engagement with the rack-bars, and, by simple connections to be described, said bail is actuated either by operation of a tabulating key, a non-computing key, a case-shift key or while the computing mechanism is going through a machine cycle. One advantage gained by silencing the computing mechanism in this manner is that the means involved are more simple, and consequently cost less for manufacturing and maintenance than the means heretofore used.

The various features of the invention are shown applied to a standard machine, which has two sets of computing wheels operated by two sets of rack-bars requiring two sets of thrust-rods. The upper ends of said rods are arranged in two rows directly behind the upper ends of the usual row of denominational tabulating stops. From each of said two rows a set of thrust-rods is directed toward a corresponding set of rack-bars, a set of rack-bars being arranged at each side of the computing mechanism leaving a substantially unoccupied space between said sets.

Another object of the present invention is to operate the computing mechanism by power-driven means that may be placed in the unoccupied space between the two sets of rack-bars. Said power-driven means include an electric motor geared to the usual operating cross-shaft of the computing mechanism. To this end, said shaft has mounted thereon a gear sector meshing with a rack which forms part of a member mounted for a reciprocating movement which is imparted to said member in the usual manner by a revolving roller and slot device, the slot being formed in said member at right angles to its direction of movement and the roller being one end of a worm and gear train driven by the electric motor through the usual clutch. Said clutch is of the type shown in the patent to A. J. Wood, No. 1,299,646, dated April 8, 1919. Devising the power-drive in this way so that it may be placed within the space occupied by the computing mechanism proper makes possible a compact machine, which has the advantage of being portable, of requiring less room and of being economically manufactured.

Another object of the present invention is to provide improved means whereby a circuit is automatically closed to start the motor simultaneously with the engagement of the clutch for a computing machine cycle, said circuit being automatically broken at the end of said cycle. As shown in the aforesaid patent to Wood, the clutch includes a driving ratchet directly geared to the motor and

a rotatable, driven member connected to the computing mechanism by the aforesaid roller and slotted member. The engagement of the driving ratchet and driven member is effected by a slight rotation of a disk. This slight rotation is imparted by means of a spring between the driven member and the disk when a bolt which normally restrains the disk against said rotation is withdrawn. Said slight rotation causes pawls on the driven member to be engaged by the ratchet. As shown in said patent to Wood, said rotation causes contacts to close and complete a circuit to start the motor. These contacts are confined within the clutch casing, and are practically inaccessible unless the clutch casing is taken apart.

Means are provided whereby contacts to close and open the motor circuit may be operated otherwise than by the rotation of the aforesaid disk, so that said contacts may be placed elsewhere than in the clutch casing. Contacts within the clutch casing besides being inaccessible are subjected to undesirable contact with the lubricant in said casing. There is provided accordingly a pair of contacts, one of which is spring-pressed and normally held separated from the other by a latch member. Said latch member is withdrawable by the same means that withdraw the aforesaid bolt to engage the clutch. This withdrawal of said latch member causes the spring-pressed contact to be released and close with a snap on the other contact simultaneously with the engagement of the clutch. During the ensuing computing machine cycle the latch member by suitable means to be described is caused to move and overhaul the released contact, and be in position to retract said contact and thereby break the circuit at the end of said cycle. This retraction of the contact opens the circuit and is effected with a snap movement as will be shown. It will be understood that the cycle is caused to be terminated at the end of one revolution of the clutch by permitting the aforesaid bolt to intercept the usual projection on the aforesaid disk, as shown in said patent to Wood.

Another object of the present invention is to provide improved means whereby the usual clear sign character may be printed when all the dial wheels of a register stand at zero. Said improved means enable the printing of said character to be done by regular finger operation of a key-lever instead of said key-lever being actuated by means of a spring and other devices and restored during a machine cycle of the computing mechanism, as shown in the patent to R. F. Hoyt, No. 1,256,309, dated February 12, 1918.

In the present invention two keys and two key-levers of the regular keyboard are used to print asterisks or stars of different designs, one for each register. An interponent

under each of said two key-levers is in position to thwart the operation of said key-levers, if the corresponding registers are not clear. If a register is clear, the interponent 5 is caused to be withdrawn by means of a link which connects it to the usual bail, shown in said patent to Hoyt. Said bail is spring-pressed against the usual row of detents which locate the dial wheels in their digit 10 positions by means of the usual detent notches in the dial wheels. The detent notch corresponding to the zero position of a dial wheel is more indented than the other notches; consequently when all the dials are at zero, the 15 bail, bearing against the detents, has assumed a position which causes the aforesaid interponent to be withdrawn.

A feature related to the star key-levers is the simple means whereby said levers when 20 operated also cause the restoration of any pins that may have been idly set in the computing mechanism rack-bars. It will be understood that such idly set pins, if not restored, would cause the corresponding register 25 to indicate a result not in accord with the figures regularly entered therein. Thus the printing of a star not only indicates that the register is cleared, but it also indicates that no pins are set when a star is printed, and 30 the means whereby the restoration of any idly set pins is thus accomplished include a simple cam that may be on the end of and part of each star key-lever. Said cam engages the end of the interponent which is in 35 the form of an arm of a bell-crank lever and rotates it so that the other arm of said bell-crank lever engages and actuates the pin-restoring connections related to the elimination key.

40 Said elimination key which is another feature of this invention is preferably a rod movable endwise and is connected to the usual pin-restoring means by means consisting of a bell-crank, one arm of which is engaged and moved by the endwise movement of the elimination key-rod. The other end of the bell-crank by means of a simple link is connected 45 to an arm by which the usual pin-restoring platform shaft, shown in said patent to Hoyt, may be operated. The elimination key on its 50 return stroke operates the usual starting key to initiate a machine cycle of the computing mechanism to cause the restoration to normal 55 of all parts of the computing setting mechanism. To operate the starting key the elimination key-rod is provided with a by-pass pawl that is ineffective to actuate said starting key on the forward stroke of the elimination key.

60 Other features and advantages will herein-after appear.

20 15 In the Underwood-Hanson bookkeeping machine numeral keys 15 and alphabet keys 16 swing key-levers 17 about a fulcrum 18, thereby causing bell-cranks 19 to swing about a fulcrum 20 and operate type-bars 21. Said 25 type-bars when operated swing upwardly and forwardly about a fulcrum 23 to print against a platen 24. Said platen is revolubly mounted in a carriage 25 which is movable on rails 26 and 27 in a letter-feeding and reverse direction.

The carriage is pulled in said letter-feeding direction by a spring motor, not shown. The letter-feeding steps of the carriage are controlled by an escapement mechanism that 30 includes an escapement wheel 30 controlled by a loose dog 31 mounted on a dog-rocker 32 which also embodies a fixed dog 33. Said dog-rocker is pivoted at 34 for a rocking motion imparted to it by the universal bar 35. 35 A rearward extension 36 of said universal bar is supported and guided by a U-shaped frame 37 pivoted at 38. The universal bar 35 is actuated in the usual manner by a heel 39 of any operated type-bar. The usual Underwood denominational tabulating mechanism includes a plurality of tabulating keys 40, which are mounted on key-levers 41 partly shown in Figure 1.

45 The rearward extensions, not shown, of said key-levers 41 when operated elevate the usual denominational stops 42 to cause the upper ends 43 thereof to be projected into the path of the usual tabulating counter-stops 44, which have features to be described later on. 50 Said counter-stops are settable in the usual notched bar 45 supported between brackets 46 projecting from the typewriter-carriage 25. The denominational stops 42 actuate the usual universal bar 50, which is mounted 55 on a shaft 51 that is rotated to cause the engagement of the usual speed governor, not shown, whereby the speed of the carriage during a tabulating movement thereof is governed. Connection to said speed governor 60 is effected by a link 52, partly shown, and an arm 53.

65 Each numeral key-lever has depending therefrom the usual stem 54. Said stem when a numeral key is operated is thrust downwardly to engage an arm 55, and thereby ro-

tate a rock-shaft 56 of a pin-setting frame generally indicated at 57. There is a rock-shaft 56 for every significant key-lever, and operation of said rock-shaft causes a corresponding pin-setting bar 58 to be depressed. 70 The pin-setting bars, of which there is one for every significant numeral key-lever, overlie a bank of index-pins 59, nine of which are in each rack-bar 60. The pin-setting bars 58 are normally slightly forward of the corresponding transverse rows of index-pins. To enable an index-pin to be set in any rack-bar, said rack-bar must be advanced slightly, so that the pins therein lie directly under the pin-setting bars. The rack-bars are thus advanced or selected one after the other in denominational order as the typewriter-carriage moves through a computing zone. 75

To accomplish this denominational selection of the rack-bars, a tappet 63 engages the upper ends 64 of thrust-rods 65 as the typewriter-carriage passes through said computing zone, and as the tappet overrides said upper ends 64, one or two thrust-rods, each corresponding to a different register, are 80 caused to be depressed at the end of each letter-feeding step of the carriage through a computing zone.

85 As shown in Figures 3 and 4, the upper ends 64 of different sets of thrust-rods are arranged in rows, one row being forward of the other to form one zone in which all of said ends are included. Said zone of the upper ends of the thrust-rods is contiguous to the denominational tabulating stops 43. Any 90 one of the counter-stops 44, which co-operate with the denominational stops 43, may therefore also include the tappet 63, which engages the upper ends of the thrust rods or jacks 65, and said tappet 63 may be wide 95 enough to actuate more than one row of jacks simultaneously, as indicated in Figure 12, or it may be formed to operate only one row of jacks 65, as indicated in Figure 8 or 9. 100 As indicated in Figures 3 and 4, the different sets of thrust-rods may, by oblique reaches 105 49 of the individual rods, diverge from the one zone in which the upper ends of all the jacks are arranged, and thus may extend outwardly and downwardly to their respective 110 sets of spaced-apart computing mechanism members for connection thereto. The upper ends 64 of the thrust-rods may be guided in a plate 61, in which are guided also the tabulating stops 43. Application of the feature of bringing all the thrust-rod sets to a common zone is not limited to only the two sets of thrust rods or jacks illustrated because it will be readily understood that more 115 than two sets of rods may be so arranged, the number of rows of upper jack-ends in said common zone corresponding to the number of individual sets of jacks. 120

125 The thrust-rods when depressed rotate levers 66, connected to the lower ends of said 130

thrust-rods. Said lower ends may be in the form of lugs 62 having screw holes into which the end thrust-rods are threaded, said screw holes enabling adjustment of the effective lengths of the thrust-rods. The levers 66 are mounted on a common fulcrum shaft 67, and have arms 68 which engage arms 69 of transposing levers 70. Said transposing levers are for the purpose of inverting the order of 10 operation between the thrust-rods and the corresponding rack-bars. Said inversion is necessary because the typewriter-carriage moving in letter-feeding steps actuates the thrust-rods from right to left, but the corresponding rack-bars must be denominational 15 selected and advanced in an order beginning from left to right.

An arm 69 of each of said transposing levers 70 is substantially in the plane toward 20 which the corresponding thrust-rod is normally directed, and an arm 71 of the same lever is in a plane adjacent to the corresponding rack-bar. Arms 69 and 71 of each pair are connected by a U-shaped yoke 72. The 25 yokes of the different levers vary in depth, as shown in Figure 3, and are disposed in groups, the yokes of each group nesting one within the other. Rotation of one of the transposing levers 70 is effected when a 30 thrust-rod 65 is depressed. This rotation causes a thrust-bar 73, connected to the arm 71, to be thrust forward and thereby advance a rack-bar by means of a projecting pin 74 fastened in the side of said rack-bar. A 35 rack-bar is held in its denominational advanced position until, by operation of any numeral key, the carriage escapes and advances a letter-feeding step and thereby causes the advance of the next rack-bar, the 40 previously advanced bar being thereupon retracted by a spring 78^a. One end of the thrust-bar 73 is pivotally supported by the corresponding arm 71 at 75. The other end of each thrust-bar has a slot 76 which em- 45 braces a bail-rod 77 by means of which said other end may be withdrawn from the pin 74. By such withdrawal every thrust-bar 73 and the train of parts leading to it are 50 silenced as pin-setting elements by operation of said bail-rod. The bail-rod 77 is supported by arms 79 fastened to a rock- 55 shaft 80.

There is a separate bail-rod 77, with supporting arms and shaft, for each set of rack-bars. According to the present form of the 55 invention the bail-rods are connected for simultaneous operation by a U-shaped frame 82 loosely mounted upon a shaft 83 and having at each end a forked arm 84 which engages the bail-rod 77. The transporting 60 levers 70 are mounted on a common fulcrum-shaft 70^a that may be suitably supported from the cross-member 86.

To prevent overthrow of the transposing 65 levers 70, the arm 69 of each lever is stopped

by the end of an adjustable screw 78 shown in Figures 11 and 12. The screws for adjusting all the transposing levers of a set rack-bars are arranged in rows separated by a plate 81 which coacts with the squared heads 70 of the screws to secure their adjustment against change. The screws are threaded through a cross-member 86 and the plate 81 may be held in place by screws 81^a. The plate 81 is removed when the screws 75 78 are being adjusted.

The shaft 83 on which the U-shaped frame 82 may be loosely mounted is supported in bearings 85 erected upon the cross-member 86 which connects the usual side frames 87 of which the left-hand one is shown in Figure 3. The left-hand rock-shaft 80 has fastened to it an arm 88 which has at its end a pin 88^a. Said pin 88^a is engaged by an arm 89 of the usual lever 90, which is rotated from its normal position at the beginning of a computing machine cycle and is latched by an arm 91, the end of which falls behind a block 90^a fastened to said lever 90. At the end of said computing machine cycle, the 90 arm 91 is withdrawn from the lever 90, by means of an extension 92 of said arm 91. Said extension 92 is struck by a tab 93 of the left supporting bracket 94 of the general operator 95 at the end of said computing 95 machine cycle, thereby causing the arm 91 to be rotated and withdrawn as stated. To rotate the lever 90 at the beginning of the computing machine cycle, said lever is provided with an arm 96 having at the end thereof a roll 97. Said roll normally lies in a notch 98 in the left-hand rack 99 of the general operator frame. When the general operator 95 advances, by means of said rack 99, the roll 97 is displaced and caused to ride 100 out of the notch 98, thereby rotating the lever 90 which is pivotally mounted on the side frame 87. The general operator 95 has a reciprocating movement and at the end of its return stroke the lever 90 is released in the 105 manner described, allowing the roll 97 to fall back into the notch 98 as said lever is retracted by means of a spring 100. Thus, it will be seen that substantially throughout a computing machine cycle the lever 90 is displaced from its normal position, thereby 110 causing, by means of the aforesaid arms 88 and 89, the rock-shafts 80 to be rocked. Consequently, throughout said computing machine cycle, the thrust-bars 73 are caused to 115 be withdrawn from the pins 74 of the rack-bars, thereby silencing the denominational selecting elements. Said elements are also silenced on other occasions in a manner to be described.

When index-pins have been set in the rack-bars, by operation of the numeral-keys, the lower ends of the set index-pins project below the rack-bars and lie in the path of the general operator 95 which is now caused to 120 125 130

move forward and back. The forward movement of said general operator is transmitted to said rack-bars which thereby move through a number of digit-spaces depending upon the pins that were set. As said rack-bars move forward they rotate the dial-wheels 102 by means of pinions 103, said pinions having the usual ratchet connections, not shown, to the dial wheels 102 whereby said wheels are rotated only during the forward movement of the rack-bars. The number of digit-spaces that each dial wheel is rotated depends upon the extent of the forward movement of the corresponding rack-bar. At each digit-space the dial wheel is detented, by means of a spring-pressed detent-lever 104, co-operating with detent-notches 105 formed on the side of each dial wheel. The detent-notch corresponding to the zero position of each dial wheel is more indented than the other notches, thereby causing a corresponding displacement of the detent-lever 104 when the dial wheel is at zero. When all of the dial wheels of a register stand at zero, said corresponding displacement in the position of all the detent-levers 104 causes a bail 106, which is spring-pressed against said detent-levers, to assume a corresponding position. Thus, the bail 106 has one position when all the dial wheels stand at zero, and another position when one or more dial wheels are rotated past zero. The displacement from one position to another of the bail 106 is used to actuate an interponent 107, and causes said interponent to be in either one of two positions. In the one position, as shown in Figure 1, said interponent clears the end of a corresponding key-lever 108 so that said key-lever is free to be operated. This condition occurs when all the dial wheels stand at zero. Should any dial wheel of a register be at a position other than zero, the corresponding detent-lever 104 is moved, causing the bail 106 to assume a different position which is effective to bring the interponent 107 into position where its end 107^a underlies the end of the key-lever 108, and thereby thwarts the operation of said key-lever as shown in Figure 2. Thus it will be seen that the key-lever 108 is operable only when all the dial wheels of the register which control it stand at zero, and said key-lever may be used to print an asterisk or star as an indication that said register is clear. The machine herein illustrated has two registers, and two key-levers 108 of the regular keyboard are used, each of which prints an asterisk or star of different design, one for each register. Each star key-lever is controlled by its own interponent 107, each interponent being in turn controlled by the bail 106 of the corresponding register. When a star key-lever is operated it is also desirable to actuate the usual pin-restoring platform, so that any index-pins which may have been idly set are restored. The means

whereby this is accomplished will be described later on. Connection between the interponent 107 and the bail 106 is effected by means of a link 110 which connects an arm 111 to one of the side arms 112 of said bail. 70 The connection to said side arm is made by means of a pin-and-slot connection 113, so that the bail 106 may be moved independently of the link 110 in a manner to be described. A spring 114 keeps the pin of said pin-and-slot connection normally engaged with the end of the slot. 75

The usual means for silencing the computing mechanism, shown in the patent to A. G. Kupetz, No. 1,452,162, dated April 17, 1923, 80 include a non-computing key or lever 115 (see Figure 1), which is pivoted to the left-hand typewriter side frame at 116. Said lever 115 has an arm 117, which embraces a pin 118 projecting through a hole in the end of an arm 119, loosely mounted on the operating shaft 120 of the computing mechanism. Same arm 119, in order to be extensible for reasons to be described, is made of two parts, one of which 121 is slidably mounted upon another part 122. When the non-computing lever is operated to silence the computing mechanism, it is rotated counterclockwise and assumes the position indicated in Figure 10. In said position the upper part 121, through which the pin 118 projects, is displaced with said pin, causing a bar 124 in which said pin is fastened to be thrust rearwardly and latches by means indicated at 125. The bar 124 in its rearward position causes a lever 126 to be rotated and displaced from its normal position. Said lever is a part of the usual means for silencing the automatic starting mechanism, shown in said patent to Kupetz, and in the present invention is provided with an arm 127, which, by means of a link 128, is connected to an arm 129 fast to the right-hand rock-shaft 80. Thus, there is a train of parts operated by setting the non-computing lever 115, whereby the rock-shaft 80 is caused to be rocked. Said rock-shaft, as heretofore mentioned, actuates the bail-rods 77 to cause the withdrawal of the thrust-bars 73. In this manner the denominational selecting mechanism 110 and consequently the computing mechanism is silenced by setting the non-computing lever. Said non-computing lever is restored to its normal position in a machine cycle of the computing mechanism which causes means to be operated, as described in said patent to Kupetz. Said means include a cam 133 fastened to the operating cross-shaft 120. Said cam, as the cross-shaft rotates during the computing machine cycle, raises the upper part 121 of the arm 119, thereby causing the bar 124 to be released from the latching means 125. The bar 124 and its connected parts are then retracted by means of a spring 134. The usual spring 135 retracts the 115 120 125 130 135

lever 126, thereby allowing the train of parts connected to the arm 127 to restore the thrust-bars 73 to their normal positions. The denominational selecting mechanism is also silenced by the operation of any one of the tabulating keys 40, so that said denominational selecting mechanism may not be actuated during a tabulating movement of the typewriter-carriage in a computing zone. To this end, the rock-shafts 80 are caused to be rotated by the operation of any of the tabulating keys 40, to effect the withdrawal of the thrust-bars 73. To rotate said rock-shafts 80 by operation of any of the tabulating keys 40, there is connected to the usual universal bar-shaft 51, which is rocked whenever a tabulating key is operated, an arm 136. Said arm 136 by means of a link 137 is connected to an arm 138, which is an extension of the arm 79 which supports the left-hand bail-rod 77, shown in Figure 3. Thus, operation of any one of the tabulating keys 40 causes the bail-rod 77 to be actuated to withdraw all the thrust-bars 73 and thereby silence the denominational selecting mechanism. It will be understood that operation of either bail-rod 77 causes the other bail-rod to be operated by means of the aforesaid U-shaped frame 82. The arm 138 has at one end thereof a slot 140 which permits rotation of said arm 138 independently of the link 137. In a similar manner the arm 129 may be slotted, so that said arm 129 may be rotated independently of the link 128.

35 A feature of the invention is the provision of simplified means whereby the functions of an elimination key 141 are accomplished. Said elimination key as usual projects through a front plate 142 of the computing mechanism, and, for the purpose of the present invention, is fastened to the end of a rod 143, the rear end of which has a bent-over tab 143^a which is slotted in order to be guided by a shoulder-screw 144 fastened into the upper cover 145 of the computing mechanism. One of the functions of the elimination key is to directly restore by operation of said key any index-pins which may have been set, said restoration to be effected independently 45 of a computing machine cycle. A computing machine cycle is initiated by the return stroke of the elimination key, after the forward stroke of said key has restored the index-pins, said cycle being thus initiated in order to re-50 store all parts of the computing mechanism to normal condition. The usual means for restoring said index-pins during a regular computing machine cycle include a pin-restoring platform 146 for each set of rack-bars 60. Said platform by the usual means shown in the aforesaid patent to Hoyt is capable of being moved upward against the lower ends of the index-pins to effect restoration of said pins. The pin-restoring means 65 also include a rotatable shaft 147 upon which

is fastened, adjacent each restoring platform 146, an arm 148. The end of said arm engages a tab 149 projecting from the restoring platform 146. To cause said shaft 147 to be rotated by operation of the elimination key 141 and thereby raise the restoring platform 146, there is fastened to said shaft an arm 150. Said arm is connected by means of a link 151 to a bell-crank 152, which is pivoted upon a stud 153 fastened in the right-hand computing machine frame, not shown. A vertical arm 154 of said bell-crank is engaged by a projection 155 of the rod 143. When the elimination key 141 is operated in a forward stroke thereof, the bell-crank 152 is rotated, and consequently the restoring platform 146 is raised to restore any index-pins that may have been set. Means whereby a computing machine cycle is initiated by the return stroke of the elimination key will be described later on.

As already stated, operation of any star-key also restores any index-pins that may have been set, and this is accomplished by causing the bell-crank 152 to be rotated by 90 operation of either star-key-lever 108.

To this end, the end of each key-lever 108 is provided with a cam 108^a. Said cam, when a key-lever is operated, is effective to rotate the corresponding interponent 107 counterclockwise. A pin 156 is driven into the end of an arm 157, and each end of said pin overlies a corresponding arm 159 of each interponent 107. The arm 157 is connected to the bell-crank 152 by a hub 158. Operation of any star-key-lever 108, by means of the parts just described, causes the restoring platforms 146 to be elevated with a consequent restoration of any index-pins which may have been set. It will be noted that one of the interponents 107 is fastened to a shaft 109. The other of said interponents, of which there are two, is loosely mounted on said shaft, and has a direct connection to the link 110 by means of a U-shaped extension 101. The interponent which is fastened to the shaft 109 is connected to its corresponding link 110 by means of an arm 109^a, which is also fastened to the shaft 109. The connections from each interponent to its corresponding bail 106 are shown in Figure 3. The shaft 109 may be supported between suitable extensions 110^a of the side plates 111^a which frame the dial-wheels 102.

Means for driving the computing mechanism by power include an electric motor 160 which is mounted at the rear of said computing mechanism in the substantially unoccupied space between the two sets of rack-bars. Besides furnishing power to drive the computing mechanism, said motor 160 may, by means of a belt 161, be connected to drive the usual carriage-return mechanism, not shown. Said carriage-return mechanism includes the usual gear-reduction mechanism

contained in a housing 162 fastened to the rear frame of the typewriter. The motor is operated only when a clutch that connects said motor to the computing mechanism is engaged. Said clutch is of the type shown in the aforesaid patent to Wood, and includes a worm 165 keyed to a shaft 166 which is flexibly coupled by the usual means (not shown) to a motor-shaft 167. The worm 165 meshes with the usual worm-wheel 168 which is rigidly connected to a ratchet 169. Said ratchet by means of pawls 170 may drive a member 171 upon which said pawls are mounted. The pawls 170 are normally held out of engagement with the ratchet 169 by pins 172 driven into a disk 173, which is normally held in such position as to keep the pawls 170 disengaged from said ratchet 169. To hold said disk 173 so that the pawls 170 are disengaged, there is provided the usual bolt 174, and in the present invention said bolt is formed upon an arm 175, which is fastened near one end of a shaft 176 that has its bearing in a portion of a frame 177 that includes a clutch casing 178. A torsion spring 179 between the arm 175 and the frame 177 is effective to urge the bolt 174 into the path of a projection 180 that is formed upon the disk 173. The clutch is engaged in the manner illustrated in the aforesaid patent to Wood, when the bolt 174 is caused to be withdrawn by operation of the usual starting key 181. The means by which said starting key effects the withdrawal of the bolt 174 include the usual starting key-lever 182 connected to the starting key-stem 183. Said starting key-lever is effective to rotate the shaft 176 to effect withdrawal of the bolt 174 by means of an arm 184 fastened to said shaft 176, the arm 184 being engaged by a stud or roll 185 which projects from the side of the starting key-lever 182. The starting key-lever 182 is pivoted in the usual manner to the right-hand computing machine frame (not shown) at 186.

Operation of the starting key 181 not only withdraws the bolt 174 to engage the clutch, but the circuit to the motor is also closed and the motor thereby started by means which include a contact device generally indicated as 187. Said contact device includes a pivoted lever 188 which has at its free end one of a pair of contacts 189, said contacts being normally separated, as shown in Figure 13. The perspective diagram, Figure 16, shows the means whereby said contacts are normally held separated, said means, in the preferred form of the invention, including a vertically movable bar 190 which is notched to embrace an insulating block 191 fastened upon the lever 188. To constrain said bar 190 to move up and down in order to open and close the contacts 189, said bar is pivotally fastened at one end to an arm 192 which is mounted upon a shaft 193. Said shaft 193 is

pivotedly supported between the side walls of the casing 194 of the contact device. The lower end of said bar 190 is constrained to move in a slot in the bottom wall of said casing 194. The arm 192 has at its outer end a tab 196, by means of which said arm is upheld by a hook-shaped member 197 that is pivoted upon one end of an arm 198. The hook-shaped member 197 is connected by a link 199 to the arm 175 upon which the bolt 174 is formed. Consequently, when said bolt is withdrawn to engage the clutch, the hook-shaped member 197 is withdrawn from the tab 196. This withdrawal of the hook-shaped member 197 from the tab 196 permits the arm to which the bar 190 is fastened to rotate with a consequent closing of the contacts 189 and starting of the motor, said rotation being urged by a torsion spring 202, one end of which reacts against the contact lever 188, and the other end of which reacts against a suitably insulated portion of the casing 194. In this manner, the clutch is engaged and the motor started, and, in the ensuing cycle of the computing mechanism, the general operator which includes the rack 99 moves forwardly in the direction of the arrow in Figure 16. This, as already explained, causes the lever 90 to rotate when the roll 97 thereof is displaced from the notch 98. Rotation of the lever 90 causes rotation of a shaft 203, to one end of which the arm 198 is fastened. To rotate the shaft 203 by means of the lever 90, said shaft, at the other end thereof adjacent to said lever 90, has fastened to it an arm 204, at one end of which is a pin 205 that follows the roller-arm of said lever 90. Consequently, when said lever 90 is displaced during a computing machine cycle, the shaft 203 is free to rotate counterclockwise of Figure 16, under the influence of a suitable spring 203^a, and said rotation causes the hook-shaped member 197 on the end of the arm 198 to move downward with said end to overhaul the tab 196 and be in position to retract the arm 192, of which said tab is a part, and thereby effect separation of the contacts 189 at the end of a computing machine cycle. This separation is effected with a snap movement at the end of said cycle when the arm 91 releases the lever 90 at the end of a computing machine cycle in a manner already explained.

The computing mechanism in the present form of the invention is connected to the driven clutch-member 171 by means which include a disk 206, which may be connected to said driven member 171 as shown in Figure 18. Eccentrically fastened to the outer side of the disk 206 is a roller 207. When the computing mechanism is in its normal or at rest position, said roller is on a line that passes through the center of said disk and coincides with the direction of movement of a member 208 which said roller as it revolves about the axis of the disk drives in a reciprocating

movement that has the same direction as the reciprocating movement of the general operator 95. In order that said general operator may be operated independently of said roller, the member 208 is provided with a longitudinal slot 209 that extends in the direction of said movement of the general operator. The slot 209 intersects at right angles a slot 201 by means of which and the roller 207 said member 208 is given its reciprocating movement. The rearward end of the member 208, when said member is in its normal position, is supported and retained by a block 210 that is supported and retained by a shoulder-screw 211 that is threaded into the center of the disk 206 and rotates therewith. Said block 210 fits the slot 209 of the member 208. The forward end of the member 208 has a longitudinal slot 212 which fits over a suitable guide 213 erected upon a cross-member 214, Figure 1, of the computing mechanism. The member 208 has formed upon its upper surface a rack 215, which meshes with a sector 216, fastened to the usual operating shaft 120 of the computing mechanism. Said shaft has at either end the usual sector 218, which, by means of an intermediate pinion 219 meshing with each sector, drives the rack 99, which is provided on either side of the machine, and thereby the general operator 95.

A detent is provided to locate the unit formed by the driven member 171 and the parts connected thereto in its normal or idle position when the clutch is not engaged. Said detent consists of a suitably heavy spring 222, one end of which is perforated so that it may underlie the head of the shoulder-screw 211, as shown in Figure 19. The other end of the spring overlies and presses the suitably-shaped end of a detent-pin 223 into a corresponding recess formed in the end of a stud 224, upon which the roller 207 is pivoted. The detent-pin fits in a counterbored hole 225 that is formed in an extension of the block 210 over the roller 207. The pin 223 has at its outer end a shoulder which fits a hole in the end of the detent-spring 222. Another shoulder 226 of the detent-pin 223 fits the counter-bore of the hole 225 and prevents said pin from being thrust entirely through the block 210.

A computing machine cycle may be automatically initiated by the usual means shown in the aforesaid patent to Kupetz, said means including a lever 220 which is actuated by a movement of the typewriter-carriage when said carriage reaches the end of a computing zone. To actuate said lever 220 in this manner, one of the tabulating stops 44, in the usual manner, engages the end of said lever and rocks it. By means of a link 221 said lever, when rocked, causes the usual parts shown in Figure 20 to be operated. Said parts include the vertically-movable bar 228, which, when operated by withdrawing

the latch-bar 229 from the end 230 of a lever 231, actuates an arm 232 of the present invention, and thereby effects the engagement of the clutch and the starting of the motor, said arm 232 being fastened to the end of the shaft 176. Said lever 231 is silenced by the operation of the non-computing lever 115, which, when operated, causes the usual lever 126 to thwart the operation of said lever 231. The usual attachments, some of which are not shown, on the lever 126 provide the obstruction which opposes the operation of said lever 231. The lever 126, as already explained, is provided with the arm 127 which forms a part of the means whereby the denominational selection of rack-bars 60 is silenced.

The means whereby the elimination key 141 in its return stroke initiates a computing machine cycle include two arms 233 and 234, said arms being spaced apart and rigidly connected by a cross-tie 235. The arms are pivoted on a post 236 erected on the upper cover 145 of the computing mechanism. A pin 237 in the end of the arm 234 connects said arm to the starting key-stem 183 in a manner shown in the aforesaid patent to Kupetz. The end of the arm 234 is provided with a by-pass pawl 238 which is diverted during the forward stroke of the elimination key by a pin 239 projecting from the side of the rod 143. On the return stroke of the elimination key and its rod 143, said pin 239, by means of said by-pass pawl 238, rocks the arms 233 and 234, and thereby depresses the starting key-stem to initiate a computing machine cycle. A spring 240 moves the elimination key and its rod 143 in the return stroke. The by-pass pawl 238 is divertible by swinging about a pivot 241 and is provided with a stop-pin 242. An extended portion 243 of the by-pass pawl acts as a counter-weight to hold the pawl in its normal position.

The usual subtraction-setting mechanism is of the type shown in the patent to O. Minton, No. 1,280,065, dated September 24, 1918, and includes a subtraction-setting key 244 on the end of a rod 245, which projects rearwardly, and is connected to an arm 246, as shown in Figure 20. Operation of the key 244 is effective to cause rotation of a shaft 247, which has fastened to it at one end the arm 246, and midway thereof the usual latch 248 which holds a subtraction-setting bar 249 against the tension of a spring 250. The subtraction-setting bar 249, when released by operation of the key 244, moves rearwardly under the influence of the spring 250, and the rearward movement is effective to set the computing mechanism for subtraction by means not shown.

During the computing mechanism cycle in which an amount is subtractively registered, the subtraction-setting bar is retracted by the

general operator 95, said general operator, in its forward movement, engaging a projection 255 on the subtraction-setting bar. Should the computing mechanism be set for subtraction by inadvertently pressing the subtraction-key 244, and should an amount then be set up in the rack-bars 60 by operation of the numeral-keys, said amount may be obliterated from the rack-bars by operation of the elimination key. To cause the subtraction-setting bar 249 to be retracted, operation of the elimination key also automatically causes the computing mechanism to cycle in the manner and by the means all ready described.

The wiring between the contact-device 187 and the motor 160 is indicated at 251, Figure 1. A plug 252 is included in said wiring, and the usual connection to the line may be made to said plug. Figure 17 shows a wiring diagram.

The computing mechanism may be manually operated by the usual handle 253, indicated by the dotted line in Figure 1. Said handle 253 is attached in the usual manner to the operating cross-shaft 126.

One purpose of the pin-and-slot connection 113 and the spring 114 of the star-key mechanism is to provide a flexible connection between one of the arms 112 and the bail 106. This flexible connection yields as the teeth which form the detent notches 105 override the nose of a detent-lever 104, if the movement of the interponents 107 is limited, as shown in Figure 2, by the key-levers 108. The spring 114 also yields when operation of the key-lever 108 rotates the interponent 107 counterclockwise to restore index-pins that may have been set.

In order that operation of the numeral-key-levers shall not set index-pins in the rack-bars 60 while the platen 24 is in uppercase position, there is provided means whereby the thrust-bars 73 are caused to be shifted and thereby silenced by actuation of the case-shift mechanism, of which only the usual case-shift frame 258 is shown. There is provided accordingly, as shown in Figure 21, a linkage 259, whereby the usual case-shift displacement of said case-shift frame causes a corresponding displacement of the bail-rods 77, which, as already explained, causes the thrust-bars 73 to be shifted to ineffective positions.

The usual key-locking mechanism is of the type shown in the patent to F. A. Hart, No. 1,213,100, dated January 16, 1917, and is actuated during a computing machine cycle. Said key-locking mechanism, partly shown in Figure 1, includes the link 260, whereby the displacement of the lever 90 during a computing machine cycle causes the key-locking lever 261 to become effective to lock the numeral-keys during said cycle. Said key-locking mechanism is also actuated while

the typewriter-carriage is moving through a punctuation-space by means of the usual levers 262, which may be actuated by means of thrust-rods similar to the thrust-rods 65. Said levers 262 actuate the key-locking lever 261 by the usual means which include links 263.

Figure 22 shows an alternative design of characters to be printed by what would otherwise be the star-key-levers. This alternative design, as shown in said figure, may be numerals with a suitable border around each printed numeral to make it sufficiently distinctive.

Variations may be resorted to within the scope of the invention, and portions of the improvements may be used without others.

Having thus described my invention, I claim:

1. In a machine having numeral-keys, a letter-feeding carriage, a plurality of spaced-apart registers, a set of key-indexed means for operating each register, and denomination-selecting tappets co-operative with the carriage, the combination of a plurality of groups of denomination-rods, each group connected with a series of indexing means, operable seriatim by the tappets, the tappet-operated ends of all the rods grouped in a computing zone, from which zone the groups of rods diverge to the sets of register-indexing means.

2. In a machine having numeral-keys, a letter-feeding carriage, a plurality of spaced-apart registers, a set of key-indexed means for operating each register, and denomination-selecting tappets co-operative with the carriage, the combination of a plurality of groups of denomination-rods, each group connected with a series of indexing means, operable seriatim by the tappets, the tappet-operated ends of the sets of rods being arranged in parallel rows, said rows extending in the direction of travel of the carriage, and being grouped in a computing zone, from which zone the groups of rods diverge to the sets of indexing means.

3. In a machine having numeral-keys, a letter-feeding carriage, a plurality of spaced-apart registers, a set of key-indexed means for operating each register, and denomination-selecting tappets co-operative with the carriage, the combination of a plurality of groups of denomination-rods, each group connected with a series of indexing means, operable seriatim by the tappets, the tappet-operated ends of the sets of rods being arranged in parallel rows, said rows extending in the direction of travel of the carriage, and being grouped in a computing zone, from which zone the groups of rods diverge to the sets of indexing means, and means on the tappets operable to selectively engage one row of rods without engaging the rods of another row.

4. In a machine having numeral-keys, a

letter-feeding carriage, a plurality of spaced-apart registers, a set of key-indexed means for operating each register, and denomination-selecting tappets co-operative with the carriage, the combination of a plurality of groups of denomination-rods, each group connected with a series of indexing means, operable seriatim by the tappets, the tappet-operated ends of the sets of rods being arranged in parallel rows, said rows extending in the direction of travel of the carriage, and being grouped in a computing zone, from which zone the groups of rods diverge to the sets of indexing means, and means on the tappets operable to engage all the rows of rods to actuate the register-indexing means for all the registers.

5. In a machine having numeral-keys, a letter-feeding carriage, a plurality of spaced-apart registers, a set of key-indexed means for operating each register, and denomination-selecting tappets co-operative with the carriage, the combination of a plurality of groups of denomination-rods, each group connected with a series of indexing means, operable seriatim by the tappets, the tappet-operated ends of each group of rods arranged in rows, and all the rows of rods positioned denominational in one computing zone, from which zone the sets of rods diverge to the associated sets of register-indexing means.

6. In a machine having numeral-keys, a letter-feeding carriage, a plurality of spaced-apart registers, a set of key-indexed means for operating each register, and denomination-selecting tappets co-operative with the carriage, the combination of a plurality of groups of denomination-rods, each group connected with a series of indexing means, operable seriatim by the tappets, the tappet-operated ends of each group of rods arranged in rows and all the rows of rods positioned in denominational order in one computing zone, each rod having a vertical tappet-operated section and a vertical register-indexing means-connecting section, both vertical sections joined by a diagonal section to transmit the movements of the rods to the spaced-apart register-indexing means.

7. In a machine having numeral-keys, a letter-feeding carriage, a plurality of spaced-apart registers, and a set of key-indexed members for operating each register, the combination of a plurality of rows of index-member actuating rods, one row of rods connected with each set of indexing members and each row extending in the direction of carriage-travel and all the rows arranged denominational within a single computing zone adjacent the carriage-travel, and tappet-means on the carriage operable to simultaneously engage more than one row of rods, whereby rods of the same denomination in different rows are simultaneously actuated seriatim to

simultaneously operate different registers, as the carriage travels through a single computing zone.

8. In a machine having numeral-keys, a letter-feeding carriage, and a plurality of spaced-apart registers, the combination of key-operated digit-indexing devices, a plurality of sets of carriage-controlled denomination-selecting trains of mechanism, one set of trains for each register, said trains converging from the registers to a single computing zone in the machine, and means movable with the carriage and effective within said computing zone to operate selectively the set of denomination-trains to one register without operating another set of trains in the same zone to another register.

9. In a machine having a letter-feeding carriage and two registers spaced apart in the direction of carriage-travel and fixed relatively to said travel, each register having a series of index members displaceable one at a time by the carriage-travel in a computing zone, the combination of two rows of member-displacing denomination-determining rods, both rows extending in the direction of carriage-travel and disposed one forward of the other in the one zone between the two registers, each rod of each row having a reach for connection with a corresponding index member of the register corresponding to said row, the reaches of the two sets of rods diverging from one another and from the computing zone, and tappet-means on said carriage operable to selectively engage and actuate a certain row of said rods, as the carriage moves through the computing zone.

10. In a combined typewriting and computing machine having a plurality of registers and a letter-feeding carriage, said registers being spaced apart in the direction of carriage-travel, the combination with a plurality of sets of index members, one set for each register, said sets spaced apart like their registers, and the members of any set being actuatable seriatim by the carriage as it travels through a computing zone, of a plurality of sets of denomination-determining rods intermediate said carriage and the sets of index members, each set of rods being connected to corresponding spaced sets of said members and converging therefrom to the computing zone, the sets of rods located in said zone being arranged in parallel rows, and means on said carriage operable to predetermine the actuation of only one row of rods by said carriage-means.

11. In a combined typewriting and computing machine, the combination with a typewriter-carriage and a pair of spaced-apart computing registers, of sets of denomination-selecting trains for said registers, said sets extending from the registers to a computing zone common to both registers, and means

adjustable along the carriage for operating one set of trains independently of the trains in the other set.

12. In a combined typewriting and computing machine, the combination with a typewriter-carriage and a pair of spaced-apart computing registers, of sets of denomination-selecting trains for said registers, said sets converging from the registers to a computing zone common to both registers, and tappets adjustable along the carriage, each tappet having means extending to both sets of trains for selectively operating trains in both sets simultaneously.
